UNITED STATES PATENT OFFICE.

THOMAS JAMES CRANSTON, OF FOWNHOPE, ENGLAND, ASSIGNOR TO
THE ERA INCANDESCENT OIL LAMP COMPANY, LIMITED, OF LON-
DON, ENGLAND.

INCANDESCENT OIL-LAMP.

SPECIFICATION forming part of Letters Patent No. 632,646, dated September 5, 1899.

Application filed November 19, 1898. Serial No. 696,902. (No model.)

To all whom it may concern:

Be it known that I, THOMAS JAMES CRANSTON, a citizen of England, residing at Ringfield, Fownhope, Herefordshire, England, 5 have invented certain new and useful Improvements in Burners for Incandescent Oil-Lamps, (for which a patent has been applied for in Great Britain, dated May 24, 1898, No. 11,803,) of which the following is a specification.

This invention relates to an improved construction of burner for incandescent oil-lamps; and it has for its object to produce a more perfect and reliable blue flame than has been possible to obtain by means of constructions of such burners heretofore employed—that is to say, a blue flame that will not be affected by slight drafts, that will not smoke, and that will be extended over the greater portion of 15 the mantle and thus produce a more uniform incandescence thereof. This object is accomplished in the manner and by the means hereinafter described and claimed, reference being made to the accompanying drawings, 20 in which—

Figure 1 is a vertical section of the burner and parts in connection therewith; and Fig. 2 is a section at $\alpha\alpha$, Fig. 1.

In the drawings, $a\alpha'$ are the inner and outer 25 wick-tubes. b is the wick; $c d$, the two caps, with holes $c' d'$ at their bottoms for the entrance of air to the space between the two caps and to the space outside the outer cap, this supply being necessary to prevent outward bulging of the mantle a^2 toward the lamp-glass. These two air-currents are designated by the arrows 5 and 6. In addition to these there is also the air-current passing between the wick and the inner cap.

40 The flame-deflector tube consists of a lower portion e , by which it is fixed in the wick-tube, the portions $e' e^2$ of reduced diameter, and the flame-deflector f' , with downward-directed flange, the portion e' of the tube being 45 formed with perforations i , while the portion e^2 above the deflector is formed with perforations l . The outer cap c extends up to the

level of the deflector f' , while the inner cap d only extends to the level of the wick-tube.

The action of the burner is as follows: Air-currents 1 and 2, passing up through the lower holes of the tube $e e'$, enter into combustion with a portion of the vapors given off on the inner periphery of the wick and form the feeding-flame. Other portions of the 55 vapors pass up partly unburned through the annular opening o between the wick and the cap d and enter into combustion with the air-currents 4 and 5, passing up through the cap d and between the caps c and d , while a still 60 further portion of the unburned vapor being caught in eddy-currents formed under the deflector f' (owing to the downward-directed flange thereof) is drawn through the top row of holes under the deflector into the interior 65 of the part e' of the tube owing to the suction of the current of air rising up therein and, mixing with such air, then passes out with the same through the holes l above the deflector f' and ignites on issuing and mixing 70 with the portion of the air rising from 4 and 5 which has not already entered into combustion. This flame, combining with that produced below, forms a perfect blue flame of such a size as to extend some distance up 75 the mantle a^2 and produces the uniform incandescence thereof.

I am aware that most of the features above described are not new in themselves and have been used in numerous combinations. The 80 present invention is limited to the definite combination described, whereby the above-described advantageous action is obtained.

Having thus described the nature of this invention and the best means I know of carrying the same into practical effect, I claim—

In a burner for an incandescent oil-lamp, the combination with the wick-tube of a central air-tube e , $e' e^2$ having its lower part e fitting the inner wick-tube while its upper 90 part e' is of reduced diameter, air-holes c and d' respectively in the shoulder between the said parts e and e' and in the part e' , a flame-deflector f' with downward-projecting rim on

the tube e' above the wick-tubes a tubular extension e^2 with perforations 3 above the deflector f' , an outer cap c terminating at the level of the deflector f and having air-holes
5 c' , an inner cap d terminating at the level of the wick-tubes and having air-holes d' , substantially as described.

In testimony whereof I have hereunto set my hand in presence of two subscribing witnesses.

THOMAS JAMES CRANSTON.
